UNITED STATES PATENT OFFICE.

ROBERT JEWELL, OF LONDON, ENGLAND.

APPARATUS FOR CONTROLLING AND REGISTERING LIQUIDS DRAWN THROUGH COCKS.

SPECIFICATION forming part of Letters Patent No. 442,053, dated December 2, 1890.

Application filed June 20, 1890. Serial No. 356,095. (No model.) Patented in England August 15, 1889, No. 12,904, and in France June 11, 1890, No. 206,301.

To all whom it may concern:

Be it known that I, ROBERT JEWELL, a citizen of England, residing at 9 Victoria Road, Battersea Park, London, in the county of Surrey, England, have invented new and useful Improvements in Apparatus for Controlling and Registering Quantities of Liquids Drawn Through Cocks, (for which I have obtained a patent in Great Britain, dated August 15, 1889, No. 12,904, and in France, dated June 11, 1890, No. 206,301,) of which the following is a specification.

My invention relates to apparatus for controlling the quantities of liquid—such as spirits, wine, &c.—drawn off through cocks and to effect the registration either of such quantities or of their money value, in order to prevent fraud on the part of the servants who draw off the liquid and dispense it to the customers. Such apparatus to be of practical value must be so arranged that it will effect the registration of the discharge not only of a maximum quantity of liquid, but also of any desired different fractions of that quantity. For this purpose I construct the apparatus as I will describe, with reference to the accompanying drawings, in which—

Figure 1 shows a front view of the apparatus; Fig. 2, a back view; Fig. 3, a cross-section; Fig. 4, a part view of plate D; Fig. 5, a detached view of contact-disk S², and Fig. 6 a front view of two sets of apparatus contained in a casing.

A is a cylinder of definite capacity equal to the maximum quantity of liquid which is required to be drawn off at one time. In this cylinder are a number of taps B' B² B³, &c., passing through it at different levels, each tap being thus enabled to draw off a different quantity of liquid—that is to say, assuming the cylinder to be full and the top tap B' to be opened, this will discharge, say, two pennyworth of liquor. Then if this tap be closed and, after filling A again, B² be opened this will discharge three pennyworth, and so on, while if the bottom tap B³ be opened the whole contents of the cylinder will be discharged. These taps have an opening at b for the entrance of the liquor, and another opening b', which when the tap is

turned half-round from the closed into the open position is brought opposite the opening of a branch c' c², &c., on a pipe C, the lower end of which is connected to a discharge-nozzle C'. The relative positions of the openings b and b' are by preference so arranged that when b' is in the open or discharging position b is at the uppermost part of the tap, so that the liquid will be discharged exactly to that level.

The lower end of the cylinder A communicates by a branch pipe A' with the pipe leading to the main cask or tank situated at a higher level, from which the liquid is to be drawn, and on the branch A' is a chamber A², containing a shut-off valve A³, which is kept closed by a spring, so as to close the communication between the cask and the cylinder when the latter is full and when liquid is being drawn off, the valve being forced open against the spring, as will be presently described, when it is required to fill the cylinder again after withdrawing a certain quantity therefrom.

Bearing upon the end of the valve-spindle a is a vertically-sliding plate D, working between guides D', fixed to the cylinder. This plate has openings through which pass the projecting ends of the tap-plugs B' B², &c. On these plugs are fingers E' E² E³, &c., which in turning the tap from the closed to the open position pass the noses of spring-catches F' F², &c., pivoted on plate D, without actuating the latter; but when the tap is turned in the opposite direction for closing after the quantity of liquid has been withdrawn the finger E' presses upon the top of the catch F', and in thereby forcing plate D downward causes this to open the admission-valve A³ and allow the cylinder to be filled with liquid again. The plate D has an arm D² near its lower end, a pin on which takes into a notch in a disk G, so that when the plate is forced downward, as described, it turns the disk somewhat, so as to bring a beak G' therein behind a stop I' on the armature-lever I of an electro-magnet J, the armature being held by a spring K so that it will retain the disk G in the position shown and thus prevent the plate D from rising and the valve A³ from closing. Within the cylinder A is a float L,

carried by a support which may be composed of a pin l , Figs. 1 and 2, located near the upper end of the cylinder, and which in rising, when the cylinder A has become filled, 5 presses against a plate M, the stem of which passes through a guide on the top of the cylinder and carries an insulating-head M', on which rests a contact-piece N, to which is connected the one lead of an electrical circuit O, in which is included the electro-magnet J. The float, in pressing the plate M upward, consequently causes N to make contact with a piece N', which is pivoted to a screw P, to which the other lead of the circuit O is 10 connected. The circuit being thus closed, the electro-magnet is made to attract its armature I, and this is thereby made to release the beak of disk G, and the plate D being now free to rise it is pushed up by the spring of 15 the valve A³, so that this now closes and cuts off the further supply. In order to break the circuit of the electro-magnet again, as soon as this action is completed the plate D carries an arm d at its upper end, which on the 20 rising of the plate presses upward against a tail N² on the piece N', and in thus forcing the latter away from N breaks the circuit. 25

It is essential with the above-described arrangement, first, that it should not be possible to open one of the taps while the supply-valve A³ is open, and, secondly, that it should not be possible after opening two taps at the same time to close one tap and thereby effect the opening of the valve A³ in the manner described, while the other tap remains 30 open, as in either of these cases an unlimited quantity of liquid might be drawn without being measured and registered. This is prevented by the following arrangement: On the inner face of the plate D are fixed a number of locking-pieces Q, Q², &c., with arc-shaped faces, as shown at Fig. 4, and on the tap-plugs B', B², &c., are fixed arc-shaped cams R', R², &c. When the plate D is in the raised 35 position and the taps are closed, the cams are in the position shown at R' in Fig. 4, and in turning the tap into the open position the cam can just pass with its curved surface beneath the curved surface of the locking-piece, as 40 shown as R²; but when the plate D is down and the supply-valve is open, the locking-piece being dotted in the position shown at Q³, the cam R will, in attempting to turn open the tap, butt against the edge of Q³, 45 and consequently its motion will be arrested before it can be brought into the open position. Again, assuming the plate D to be in the raised position and that two of the taps have been turned into the open position, then 50 in turning one of these into the closed position the depression of the plate D cannot be effected by the pressure of the finger E of the tap on the catch F, as above described, because the cam R of the other open tap, being situated under the curved face of its locking-piece Q, prevents any downward motion 55 of D.

Both taps must therefore be turned so as to close the discharge-openings and bring the cams from under the locking-plates before the 70 depression of plate D and opening of the supply-valve can be effected.

For effecting the registrations on the counter according to the quantity of liquor drawn at one time, each tap-plug B', B², &c., carries 75 on its rear end a disk S', S², &c., of insulating material, on the periphery of which are contacts s, s², which are in conducting-connection with the plugs B', B², &c., and through these with the cylinder A, to which, at any convenient point, the one lead of the electric circuit T of the registering-counter is connected, while the other lead is connected to a plate U, secured in an insulated manner to the cylinder A and carrying a number of contact-springs u', u², u³, &c., which slide in contact with the disks s, s², and consequently effect 80 a closing of the circuit, so as to actuate the counter every time one of the contacts passes underneath the spring on the turning of the 85 tap. The contact-pieces s, s² may be arranged in either of two ways: either there are half as many contact-pieces as there are 90 registrations to be effected on the counter, so that one-half of the registrations are effected 95 on turning the tap open and the other half on turning it into the closed position—thus in the above-described arrangement the disk S' of tap B' would have only one contact-piece, as on turning open the tap this would 100 register one penny and on turning the tap back it would register the second penny—or the contacts may be arranged to register only 105 in one direction, in which case there would be as many contacts as there are units to 110 register. With this arrangement the disk is made loose on the sleeve by which it is connected to the plug, and the sleeve s², which is of conducting metal and is fixed to the plug, is formed with a stud s³, which fits with a 115 small amount of play in a notch in the disk S², as shown at Fig. 5, and the one side of 120 this notch is formed of insulating material, while the other side is of conducting metal, in connection with the contacts s, s². Thus on 125 turning the plug into the open position the stud s³ presses against the conducting-piece of the disk S², and consequently the contacts s in passing under the spring u² effect the closing of the circuit, as described, while on 130 turning the plug in the contrary direction for closing the stud s³ will press against the insulating material of the disk, and consequently the contacts will not effect the closing of the circuit. This arrangement requires to be used in those cases where the 135 number of contacts to be made is uneven—as, for example, with the third tap.

Although the above-described construction of measuring and registering apparatus is 140 specially designed for cases where it is desired to draw variable quantities of liquid, yet it will be evident that it may be equally well applied for always drawing one and the

same quantity of liquid by means of a single tap—such, for instance, as for bottling purposes.

Having thus described the nature of this invention and the best means I know for carrying the same into practical effect, I claim—

1. In apparatus for drawing off different definite quantities of liquid through cocks, a vessel having two or more cocks at different levels for discharging different quantities of liquid from it, a conduit connecting said vessel with a supply-tank and provided with a shut-off valve automatically closed by a spring, a sliding plate connecting the several cocks with the shut-off valve, whereby when the cocks are turned into the closed position they effect the opening of the shut-off valve, and locking-plates upon the said sliding plate operating in conjunction with cams on the cock-plugs, which prevent a cock from being opened while the shut-off valve is opened, and which also prevent the closing of a cock, so as to open the shut-off cock while a second cock remains open, substantially as described.

2. In apparatus for controlling and registering quantities of liquids drawn through cocks, a vessel having two or more cocks at different levels for discharging different quantities of liquid from it, a conduit connecting said vessel with a supply-tank and provided with a shut-off valve, a sliding plate connecting the several cocks with the shut-off valve, whereby when the former are closed they effect the opening of the latter, while when cocks are opened the shut-off valve is kept closed by locking-pieces Q' Q^2 upon the said sliding plate operating in conjunction with cams R' R^2 upon cock-plugs B' B^2 , which prevent a cock from being opened while the shut-off valve is opened, and which also prevent the closing of a cock, so as to open the shut-off valve while a second cock remains open, and a contact device connected to each cock-plug included in an electrical circuit actuating a registering mechanism or counter, whereby on opening or closing the cock contacts are made in the said circuit, so as to register the quantity of liquid drawn, substantially as described.

3. In apparatus for drawing off different definite quantities of liquid through cocks, a vessel having two or more cocks at different levels for discharging different quantities of liquid from it, a conduit connecting said vessel with a supply-tank and provided with a shut-off valve automatically closed by a spring, a sliding plate connecting the several cocks with the shut-off valve, where-

by the cocks are turned into the closed position to effect the opening of the shut-off valve, a catch retaining the sliding plate in the position for keeping open the shut-off valve, and an electro-magnet for releasing the said catch and allowing the shut-off valve to close, such electro-magnet being included in an electrical circuit which is closed by the action of a float in the vessel upon contacts when the vessel is filled, substantially as described.

4. In apparatus for controlling and registering quantities of liquid drawn through cocks, a vessel having two or more cocks at different levels for discharging different quantities of liquids from it, a disk of insulating material on the plug of each cock and carrying a number of contact-pieces adapted by the rotation of the plug to make a series of contacts on an electrical circuit including electrical registering mechanism, the number of contact-pieces on each cock being varied, so as to vary the indications on the registering mechanism, according to the particular cock through which liquid is drawn, substantially as described.

5. In apparatus for drawing off different definite quantities of liquid through cocks, a vessel having two or more cocks at different levels, a conduit connecting said vessel with a supply-tank and provided with a shut-off valve, a sliding plate connecting the shut-off valve with each cock, so that on closing the cock the plate is depressed and the shut-off valve is opened, a catch retaining the sliding plate and valve in the open position, an electro-magnet for releasing the catch and allowing the sliding plate to rise and the shut-off valve to close, an electric circuit for exciting the electro-magnet, a float in the vessel which actuates contacts so as to close the electric circuit when the vessel is full, and an arm on the sliding plate which acts on said contacts so as to break the circuit again on the rising of the sliding plate, substantially as described.

In testimony whereof I have signed my name to this specification, in the presence of two subscribing witnesses, this 9th day of June, A. D. 1890.
